UNITED STATES PATENT OFFICE.

DANFORTH FLETCHER ALVORD, OF WINSTED, CONNECTICUT.

DESIGN FOR A GRAPE-FRUIT AND ORANGE KNIFE.

41,318.

Specification for Design.

Patented Apr. 18, 1911.

Application filed January 5, 1911. Serial No. 601,051. Term of patent 3½ years.

To all whom it may concern:

Be it known that I, DANFORTH FLETCHER ALVORD, a citizen of the United States, and a resident of Winsted, in the county of Litchfield, State of Connecticut, have invented a new, original, and ornamental Design for a Grape-Fruit and Orange Knife, of which the following is a specification, reference being had to the accompanying drawing, forming part hereof.

I claim,

The ornamental design for a grape fruit and orange knife as shown.

D. FLETCHER ALVORD.

Witnesses:

J. ALBERT SMITH,
CHAS. W. CHIDSEY.
